UNITED STATES PATENT OFFICE

2,591,835

HAIR PARTING DEVICE

John Lakeland, Toronto, Ontario, Canada

Application August 18, 1950, Serial No. 180,111

3 Claims. (Cl. 132—45)

1

The primary object of my invention is to provide a toilet device which is particularly designed to part the hair of the human head in a simple and effective manner.

Another object is to provide a toilet article of this kind having long slender prongs formed in two similar groups, of which each group is carried by a holder in the nature of a grasping element. The prongs are desirably curved through their length to more nearly conform to the crown of the average human head and they are implanted in the hair by inserting them therein from the front of the head. By pulling one of the holders laterally away from the other, the prongs of the one holder draw the strands of the engaged hair away from the hair engaged by the other holder. Then by moving the other holder laterally away from the parting line, the hair is parted in a smooth and perfect appearance.

The invention is simple to use and moreover it produces an exact parting. It thus gives the hair a well-groomed and neat appearance. The parting can be carried out with exactitude, and time and labour is saved in grooming the hair.

The device is inexpensive to manufacture and is highly desirable as a toilet article for fastidious people.

A selected embodiment of the invention is shown in the accompanying drawing, in which

Fig. 1 is a view of the parting instrument depicting the manner in which the instrument is applied to the hair in a parting operation.

Fig. 2 is a plan view of the parting device.

Fig. 3 is an edge view of Fig. 2.

Fig. 4 is a plan view of Fig. 1 showing how a section of the parting instrument is pulled laterally through the hair in a parting operation.

The hair parting instrument of the present invention comprises a plurality of long slender prongs which are divided into two similar groups A and B. Group A of the prongs is carried by a holder 6, and group B of the prongs is carried by a holder 7. The prongs extend from the respective holders in parallel relation and are rigid therewith.

The article may be made of metal, plastic or other material of an approved type. The prongs may be constructed as an integral part of the holder, or on the other hand they may be attached thereto. The prongs should possess a slight degree of springiness so as to have resiliency in a direction transversely of a plane containing the prongs. The cross-section of the individual prongs should be of a shape that will

2

strengthen them against bending in a plane through the several prongs of a group. To this end the prongs may be of an oval or a flat shape in cross-section.

5 The prongs should also be of a length to extend a substantial distance through the hair adjacent to the scalp, as depicted in Figs. 1 and 2, and they should be curved through their length to more nearly conform to the contour of the crown portion of the average human head—see Fig. 3.

The holders 6 and 7 are grasping portions which form co-acting parting elements with the respective groups A and B of the prongs. Said holders abut each other at their inner ends 8 and these ends have an interfitting connection by which the two co-acting parting elements are detachably joined. The interfitting connection may for example consist of a tongue 9 on the holder 6 and a socket 10 provided in the end of the holder 7. The tongue is made a free and easy fit in the sockets so that the holders can be readily separated.

An important feature of the construction is 25 that the parting elements each have a prong located flush with the inner end 8 of the respective holder. These extreme inner prongs are contiguously engaged when the holders are brought into abutment and interconnected by means of the tongue 9 and the socket 10.

In the use of the article the two sections or parting elements are joined by means of the tongue 9 and the socket 10. In the assembled condition of the two sections the article is inserted into the hair from the front of the head and the meeting inner prongs C of the sections are located at the place where the hair is to be parted. To bring about the desired parting one of the holders is held against movement while the other holder is withdrawn through the hair in a lateral direction—see Fig. 4. The other holder is then pulled laterally through the hair directly away from the parting line, which thus provides an accurate and perfect parting of the hair. The hair is quickly and smoothly parted by the device of the invention. Moreover the device is inexpensive to manufacture and easy to use.

What I claim is:

1. A hair parting device comprising a pair of elongated holders in the form of rigid grasping members arranged in end to end relation, interfitting means on the inner ends of said holders by which they are interconnected and capable of being detached readily by pulling them apart, a main hair parting prong rigidly carried by each

holder, said prongs being located at the inner ends of said holders immediately adjacent to each other and co-extensively arranged, said prongs consisting of long slender members of stiff material for passing through the hair immediately adjacent to the scalp to create a parting, and a plurality of ancillary prongs on the holders, said ancillary prongs being arranged in spaced parallel relation and in a plane containing said main prongs to co-extend therewith.

2. A hair parting device as defined in claim 1, in which the interfitting means comprises a recess in the inner end of one of the holders forming a socket, and a tongue on the other holder, said tongue projecting axially of the last mentioned holder and being engaged slidably in said socket.

3. A hair parting device as defined in claim 1, in which the outer ends of the holders project

beyond the prongs transversely thereof in order to form grasping portions by which the device may be manipulated with facility.

JOHN LAKELAND.
